UNITED STATES PATENT OFFICE.

JAMES SMITH LANIER, OF WEST POINT, GEORGIA.

MAIL RECEIVING AND DELIVERING MECHANISM.

No. 898,487.

Specification of Letters Patent.

Patented Sept. 15, 1908.

Application filed November 2, 1907. Serial No. 400,860.

To all whom it may concern:

Be it known that I, JAMES SMITH LANIER, a citizen of the United States, residing at West Point, in the county of Troup and State of Georgia, have invented certain new and useful Improvements in Mail Receiving and Delivering Mechanism; and I do hereby declare the following to be a full, clear, and exact description of the invention, such as will enable others skilled in the art to which it appertains to make and use the same.

This invention relates to improvements in apparatus adapted for receiving and delivering articles, and is especially designed for use in the mail service.

The essential object in view is the provision of a support for a container so arranged that the container is readily accessible, and may be moved toward and from the operator without requiring his dismounting, and is adapted to assume an out-of-the-way position when released.

With this and further objects in view, the invention comprises certain novel constructions, combinations and arrangements of parts as will be hereinafter fully described and claimed.

In the accompanying drawing:—Figure 1 is a view in side elevation of an apparatus embodying the features of the present invention, the parts being shown in full lines in the position assumed when retained by the operator, and in dotted lines in the normal out-of-the-way position. Fig. 2 is an enlarged, detail, fragmentary view partly in elevation and partly in section, the pivoted sleeve being shown in section. Fig. 3 is a vertical section taken on line 3, 3 of Fig. 2, parts being seen in elevation. Fig. 4 is an enlarged, detail end view of the receptacle indicating the hanger therefor partly in elevation and partly in section. Fig. 5 is a view similar to Fig. 1 of a modified form of construction, the pivoted sleeve being shown in section. Fig. 6 is another modified construction.

Referring to the drawing by numerals, 1 indicates a sleeve which is rotatably mounted on a bolt 2 passed through and rigidly secured to a supporting post 3. The sleeve or housing 1 may be of any desired cross sectional contour, but is preferably rectangular, as indicated clearly in Fig. 3, and the bolt 2 is provided with a head 4 just inside the sleeve 1

for retaining the sleeve in position. The bolt 2 extends outwardly beyond the head 4 and at its outer end is formed with a second head 5 within the casing. The head 4 is preferably made integral with or suitably fixed to the bolt 1, but may be made in the form of a movable washer. A bar 6 extends through 60 and is slidably mounted within the sleeve 1 and is formed with a longitudinal slot 7 through which the bolt 2 extends. The bolt 2 thus serves as a stop for the longitudinal movement of the bar 6 and as a guide therefor. For further guiding the bar 6 and as far as possible eliminating friction, rollers 8 are journaled within the sleeve 1 and are disposed with their peripheries engaging the edges of the bar 6, said rollers being preferably flanged at their ends for guiding the bar 6 and preventing lateral play or twisting thereof.

The bar 1 is overbalanced at one end, as for instance by a pendent weight 9 which may be suspended from the end of the bar by a chain or other cable 10. The chain or cable 10 is adapted to be passed through any one of a set of apertures 11, spaced longitudinally of the bar 6 for increasing or decreasing the leverage of the weight for varying the counter-balancing effect relative to the weight to be suspended on the other end of the bar. To the opposite end of the bar 6 from the weight 9 is pivoted a pendent hanger 12 which consists simply of a vertical portion and a horizontal portion, the vertical portion being pivotally carried by a bolt 13 engaging the end of the bar 6 and provided with any suitable spacing sleeve 14. The horizontal portion of the hanger fixedly carries a receptacle 15 especially adapted for the receipt and delivery of mail.

In Fig. 5 I have indicated a slightly modified construction in which the bar 6' is not slotted, the pivot supporting bolt of the sleeve 1' terminating just inside the inner wall of the sleeve and the bar 6' being guided directly by the rollers 8' and being limited in its longitudinal movement by enlargements 100 7', 7'', near its ends. Fig. 6 discloses substantially the same structure with stops 7'' arranged on the bar 6'' in lieu of the enlargements 7' of bar 6'.

In operation, the bar 6 remains normally 105 in the vertical position indicated in dotted

lines in Fig. 1, the box or receptacle 15 of course remaining in a horizontal position, the weight of the box being beneath the center of gravity relative to the pivot which causes the box to remain horizontal, regardless of movements of the bar 6. When the operator wishes to remove or insert mail or other articles, he simply grasps the box or some suitably provided handle thereon and swings the same downwardly until the bar 6 arrives substantially in a horizontal position, whereupon the operator draws the bar longitudinally outwardly from the post until he has easy access to the receptacle 15. After depositing the mail or otherwise completing the operation, the operator simply releases the box, whereupon the weight 9 will cause the sleeve 1 to swing upon its pivot and thus bring the parts back to the position indicated in dotted lines in Fig. 1. In order to prevent the box 15 from swinging downwardly too far when the same is being drawn down by the operator and to prevent the bar 6 from swinging past the horizontal position, when the box 15 is released, the pin 17 is positioned in the post 3 and extends into the path of movement of the inner wall of the sleeve 1, but does not extend outwardly sufficiently far, as indicated in dotted lines in Fig. 3, to interfere with the operation of the bar 6.

Obviously the chain 10 may be made of any length desired, and if it is found that the bar 6 moves to its vertical position quite rapidly so as to cause the sleeve 1 to strike the pin 17 with considerable force, the chain 10 may be made of sufficient length for causing the weight 9 to strike the ground just before the bar 6 assumes a vertical position, and this will materially reduce the force of the blow against the pin 17. A washer or other spacing means 18 preferably surrounds the bolt 2 between the post 3 and the sleeve 1.

Obviously, the sleeve 1 may be made otherwise than as a complete, closed sleeve, and in fact it will be obvious that various forms of guides may be substituted for the sleeve shown without departing from the invention, and furthermore the bar 6 may not only be constructed as illustrated, but may be made of single iron, channel iron, T iron or otherwise as found desirable within the scope of the present invention.

What I claim is:—

1. In article receiving and delivering apparatus, the combination of a longitudinally reciprocating bar, a pivotal support for said bar, overbalancing means at one end of the bar, and a pivotally mounted receptacle carried by the opposite end of the bar.

2. In article receiving and delivering apparatus, the combination of a slidingly mounted bar, a pivotal support therefor, a

pendent weight at one end of said bar, and a pendulum receptacle at the opposite end 65 thereof.

3. In article receiving and delivering apparatus, the combination with a support, of a bar slidingly and pivotally mounted thereon, means overbalancing one of the ends of 70 the bar, and a receptacle pivotally carried by the opposite end of the bar and having the preponderance of its weight beneath the center of gravitation.

4. In article receiving and delivering apparatus, the combination of a slidingly mounted bar, a pivotal support for said bar, an adjustable overbalancing weight at one end of said bar, and a pivoted receptacle at the other end thereof. 75

5. In article receiving and delivering apparatus, the combination of a pivotally mounted sleeve, a bar extending therethrough and slidingly mounted therein, means overbalancing one end of the bar, and 80 a receptacle pivotally carried by the other end of the bar.

6. In article receiving and delivering apparatus, the combination of a pivotally and slidingly mounted bar overbalanced at 90 one end, and a receptacle sustained by the opposite end.

7. In article receiving and delivering apparatus, the combination of a support, a pin projecting therefrom, a slidingly mounted 95 bar, slotted longitudinally and having said pin extending through the slot, an overbalancing weight at one end of the bar, and a receptacle carried by the other end of the bar.

8. In article receiving and delivering apparatus, the combination of a pivotally mounted longitudinally sliding bar, means for limiting the longitudinal movement of the bar, means overbalancing one end of the bar, and a receptacle connected with the opposite end of the bar. 100

9. In an apparatus of the class described, the combination with a support, of a guide pivotally mounted thereon, a bar longitudinally slidingly mounted in said guide, means 110 for overbalancing one end of the bar, a receptacle carried by the other end of the bar, and means extending into the path of pivotal movement of the guide for limiting the same against movement farther than from a horizontal position to a vertical position. 115

10. In an apparatus of the class described, the combination with a supporting post, of a guide pivotally mounted thereon, a bar slidingly mounted on said guide, an adjustable 120 pendent weight at one end of said bar adapted to be adjusted to a position for striking the ground when the guide is pivoting to a horizontal position just prior to the guide arriving at such position, and a stop 125 for limiting the pivotal movement of the

guide for preventing greater movement thereof in one direction than a horizontal position.

11. In an apparatus of the class described, the combination with a support, of a bolt carried thereby, a guide pivotally mounted on said bolt, the bolt having spaced heads within the guide, a slotted bar slidingly mounted in the guide and having the bolt

passed through the slot thereof, overbalancing means for one end of the bar, and a receptacle for the other end thereof.

In testimony whereof I affix my signature in presence of two witnesses.

JAMES SMITH LANIER.
